Application April 6, 1933, Serial No. 664,803

7 Claims. (Cl. 221—67)

This invention has for its object, the provision of what is commonly known as a gasoline filling station, novel means being provided for storing fluid in the frame work of the building, and novel means being provided for dispensing the fluid, it being the intention to supply a device of the class described wherein a wide variety of oils, by way of illustration may be made available.

10 It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

15 In the accompanying drawings:

Fig. 1 shows in elevation, a filling station constructed in accordance with the invention, parts being broken away, and parts being in section;

Fig. 2 is a top plan, wherein parts are broken away, parts being in section;

Fig. 3 is a section taken approximately on the line 3—3 of Fig. 1;

Fig. 4 is an enlarged section on the line 4—4 of Fig. 1, parts being in elevation, and parts being broken away;

Fig. 5 is a section on the line 5—5 of Fig. 1, parts being in elevation;

Fig. 6 is a top plan showing a portion of one of the units of the base, some elements being in section;

Fig. 7 is an elevation of the auxiliary tank, parts of the building being in section;

Fig. 8 is an elevation showing a modification, parts being broken away, and parts being in section;

Fig. 9 is a section at right angles to the showing of Fig. 8, with parts in elevation;

Fig. 10 is a top plan, parts being in section, and parts being broken away;

Fig. 11 is a sectional view showing a slight modification.

In the following description, and referring particularly to Figs. 1 to 7 at this point, certain parts of the structure will first be grouped together, as a building, and then it will be pointed

out how certain of those parts have a function as oil containers, dispensing means, etc.

The building embodies a base, which is designated generally by the numeral 1. The base 1 comprises two parallel units, and one of those units is shown in detail in Fig. 6. Each unit of the base 1 comprises an outer horizontal tube 2, and an inner horizontal tube 3, these tubes being parallel. In order that the base may be lengthened, slides 4 (Figs. 3 and 6) are closely but 10 movably mounted in the ends of the tubes 2 and 3. To the outer ends of the slides 4, U-shaped extensions 5 are pivoted at 6, for up and down swinging movement, to facilitate the transportation of the structure from place to place, the 15 pivoted extensions 5 conforming readily to irregularities of the ground. With the same end in view, the edges of the extensions 5 are rounded off, as shown at 7 in Fig. 6 and in Fig. 1. A cab 8, for the convenience of the keeper of the filling 20 station, is secured to one of the extensions 5, or is mounted elsewhere.

Reverting to Fig. 6, it will be observed that the tubes 2 and 3 of the parallel units of the base 1 are connected by platforms 9, whereon are 25 mounted the columns 10 of Fig. 3, adapted for the dispensing of gasoline, or other motor fuel, in the usual way.

The side members of the base carry vertical standards 11, for the support of the roof structure, the standards preferably being placed midway between the ends of the base. The standards 11 are of composite make-up. They comprise vertical outer pipes 12 (Fig. 6) connected to and communicating with the horizontal base tubes 2, 30 and corresponding vertical inner pipes 14, connected, as disclosed in Fig. 4, with the horizontal base tubes 3. The pipes 12 and 14 may be sustained from the corresponding base elements 2 and 3 by the inclined braces 15 of Figs. 3 and 6. 40 The pipes 12 and 14 may be cross-connected by lattice braces 16, which are indicated with sufficient clarity by the dotted line showing of Fig. 1.

Hollow, horizontal frame members 17 (Figs. 5 and 1) are secured to the outer vertical pipes 12 45 and 11. Hollow beams 18 (Fig. 5) are arranged at right angles to the frame members 17. Most of the beams 18 are located between the frame members 17, but the end beams 18 extend across the ends of the frame members 17, and are secured thereto. The hollow beams 18 are not in communication with the frame members 17. Spacers 19 join the beams 18 together, as Fig. 5 will show. A ceiling 20 (Fig. 3) is carried by the beams 18. 55

On the beams 18, at right angles thereto, are placed rafters 21 (Fig. 3), the rafters being secured to the beams by brackets 22. The rafters 21 carry a roof 23, which may be sustained by 5 the inclined braces 24 of Fig. 4, and, indeed, bracing may be resorted to wherever necessary, that being a structural detail which may be left to the judgment of the builder. The roof 23 carries an upstanding marginal wall 25, to which are 10 secured the vertical posts 26 of Fig. 1, these posts supporting a narrow rigid canopy 27.

Above the roof 23 are located hollow beams 28 (Figs. 3 and 2), arranged at right angles to the rafters 21. Cap plates 29 (Figs. 2 and 1) are secured to the upper ends of the vertical pipes 12 and 14 that form parts of the roof-supporting standards 11. To enable the operator to get to the roof 23, the same is provided with a removable hatch cover 30 (Figs. 1 and 2), and the operator can climb to the hatch cover on foldable ladder rungs 31 mounted on the frame members 17, and on rectangular casings 32, forming parts of the standards 11, and surrounding the pipes 12 and 14 throughout a portion of the 25 length of the pipes, as Fig. 1 will show.

Electric lamps 33 may be placed wherever necessary, and derive their current from the electric main 34 of Fig. 3.

Two or more flexible water hoses 35 are supplied, and to their intermediate portions, flexible elements 36 (Fig. 3) are connected. The flexible elements 36 are led inwardly over pulleys 37 on the roof-wall 25, and downwardly (Fig. 4) over pulleys 38 journaled on vertical tubular guides 39, secured to the casings 32, or mounted otherwise. Weights 40 are connected to the flexible elements 36, and slide in the guides 39. The weights 40 and the flexible elements 36 draw the water hoses 35 up into the out-of-the-way 40 position of Fig. 3, but an operator can pull each hose 35 down, when there is occasion for using it to fill a radiator on a car, or for any other purpose.

Having described the frame work of the building generally, the oil-holding and dispensing structure will be co-related with the elements of the building.

Each of the horizontal tubes 2 and 3 is divided, intermediate its ends by a partition 41, shown in 50 Fig. 4. In each of the vertical pipes 12 and 14 there is a transverse inclined partition 42. There results, as a consequence, eight L-shaped storage compartments 43 for oil or the like, it being possible to fill these storage compartments through 55 street L's 44, mounted on the pipes 12 and 14, and shown in Fig. 4.

It appears in Figs. 5 and 1 that the outer vertical pipes 12 have holes 45 that communicate with the hollow frame members 17. Thus, there 60 are formed first oil chambers, composed of the hollow frame members 17 and so much of the pipes 12 as lie above the corresponding partitions 42 of Fig. 4. The oil can be drawn out of the first oil chambers above described, by means of 65 faucets 46 (Fig. 1), mounted on the pipes 12. The faucets 46 are disposed above a lower drip pan 47. There are two of these drip pans 47, as Fig. 4 will show, and they are mounted in cabinets 48, carried by the casings 32, the cabinets having 70 movable closures 49. All drip pans may have drains 80.

Passing to Fig. 3, it will be observed that there are holes 50 in the inner vertical pipes 14, the holes 50 communicating with the ends of the 75 hollow beams 28. There are formed, therefore,

second oil chambers, which comprise the beams 28 and so much of the vertical pipes 14 as lie above the partitions 42 of Fig. 4. Oil is drawn from the second oil chambers above defined, through faucets 51, carried by the pipes 14, and 5 having their own drip pan 47, located within the corresponding cabinet 48.

Third oil chambers are provided, and each of these chambers is represented by one of the hollow beams 18 of Fig. 5. Pipes 52 are connected 10 to the ends of the hollow beams 18, and lead downwardly through the standards 11 to a plurality of faucets 53, disposed above the faucets 51 and 46, and having their own drip pan 54, which may be supported on the faucets 51 and 15 46. The faucets 53, and those hereinbefore and hereinafter mentioned, are located within the cabinets 48.

A plurality of fourth oil chambers are provided, and are in the form of containers 55, supported 20 by the beams 28 of Fig. 2, and disposed beneath the canopy 27. Figure 1 shows that each of the containers 55 is connected at 56 to a pipe 57, and these pipes lead downwardly into the standards 11, so that oil from any one of the containers 55 25 may be drawn off from within the cabinets 48. The faucets for the pipes 57 are marked by the numeral 58, and are in a horizontal line with the faucets 51 and 46, above the drip pans 47.

Oil can be introduced into the first and second 30 oil chambers through filling plugs 59, disposed above the cap plates 29 of the pipes 12 and 14, and communicating with those pipes. Each of the hollow beams 18 (Fig. 3) has its own filling connection 60 (Fig. 2), located above the roof 23. 35 The filling plugs for the containers 55 are shown at 61 in Fig. 2.

Sometimes an additional supply of oil for one or more of the hollow beams 18 may be required, and then the tank 62 of Fig. 7 is used, the tank 40: 62 being joined temporarily to the connection 60, above the roof 23, by a union 63, containing a valve 64, under the control of an operator.

The filling of the various oil chambers may be brought about in the way that suits the operator 45 best. Preferably, the oil filling line 65 of Fig. 1 is joined to a vertical pipe 66, which extends upwardly through one of the standards 11, to a point above the roof 23. To the upper end of the pipe 66, a flexible hose 7 is connected, and it may 50 be coiled down on the roof, when not in use. The operator, however, can extend the hose 67 to any of the filling plugs, such as the parts 59, 63 or 61 of Fig. 2.

Air pressure can be put on the various oil chambers. This is done through a vertical pipe 68 (Fig. 1) in communication with a source of fluid pressure supply (not shown). The vertical pipe 68 is joined to a horizontal pipe 69, connected at 70 to the containers 55, and connected at 71 to 60 the vertical pipes 12 and 14 of the standards 11, through the cap plates 29.

A dispensing truck 72 (Fig. 1), useful for many purposes, is provided. It carries an air compressor 73 driven by an engine 74, or other motor. 65 The compressor 73 is connected to a pressure tank 75 having a pipe 76, with branches 77 leading to oil tanks 78 on the truck 72, each oil tank having its own outlet hose 79. If the operator wishes, he can couple either hose 79 to the oil filling line 65 of Fig. 1, 70 for the replenishment of any of the oil chambers supplied by the pipe 66 and its hose 67.

The faucets 58 draw through the pipes 57 from the containers 55. The faucets 46 draw through the vertical pipes 12 from the frame members 17. 75

The faucets 51 draw through the vertical pipes 14 from the hollow beams 28. The faucets 53 draw through the pipes 52 and the hollow beams 18.

5 In the form shown in Figs. 8, 9 and 10, the base is marked by the numeral 81, and comprises parallel units, as hereinbefore described. The units of the base embody parallel channels 82, and assembled with the channels, at one side of the base, or at both sides, if desired, is a tank 83, having a connection 84, through which the tank may be filled. The numeral 85 designates a hose which may be either the filling hose or the dispensing hose. The tank 83 carries a connection 86 for air pressure, to force the contents of the tank 83 out through the hose 85, it being possible to use the contents of the tank to fill the hollow, oil-containing members in the superstructure or for any other purpose.

10 The supporting standards for the superstructure are marked generally by the numeral 87, and comprise vertical channels or posts 88, surrounded throughout the major portion of their length by casings 89, corresponding to the casings 32. The lower ends of the posts 88 are secured to the channel members 82 of the base 81. The upper ends of the channel posts 88 are encased, as shown at 90 and the upper ends of the posts are housed by cap plates 91, corresponding to the cap plates 29.

15 On the parallel units of the base 1 are mounted dispensing columns 92, for the motor fuel, and the fuel passes to the dispensing columns through pipes 93, entering tanks 94, arranged under ground, or elsewhere. There may be as many of the dispensing columns 92 and the corresponding tanks 94 as desired. Vent pipes 95 are connected to the tanks 94, and extend upwardly between the channel posts 88 of the standards 87.

20 A foundation 96 is arranged between the parallel units of the base 81, and on opposite sides of the foundation there are guard walls 97. A cab 98 is mounted on the foundation 96 and has double-swinging doors 99. Electric lamps 100 are mounted on the cab 98, and wherever else the operator wishes to put them.

25 The superstructure comprises a rectangular frame 101, embodying inwardly facing channels 102, which may be reenforced, at the corners of the superstructure, by angle bars 103. Secured to the inner surfaces of the vertical walls of the channels 102 is a supplemental frame 112 made up of outwardly-facing channels 104. Outer Z-bars 105 are secured at their ends to the opposed members 104 of the auxiliary frame, and are secured intermediate their ends to the outer vertical posts 88. Inner Z-bars 106 bear a similar relation to the said members 104 of the auxiliary frame, and to the inner vertical posts 88, as Fig. 10 30 will show. Crossed braces 107 connect the bars 106.

35 Turnbuckle braces 108 connect the inner posts 88 with the roof frame, and similar braces 109 connect the outer posts 88 with the roof frame. A ceiling 110 is joined to the lower horizontal flanges of the channels 102 of the roof frame 101. Intermediate Z-bars 111 extend across the frame and are in line with the inner vertical posts 88.

40 Depending tubular sockets 114 are secured to the ceiling 110 and to any solid parts that lie above it. In the sockets 114 are received threaded projections 115 extending upwardly with respect to the cab 98. Specifically, the projections 115 are the upper ends of posts 116, built into the cab 98. Adjustable supports 117 engage the lower

45 ends of the sockets 114, and may be nuts threaded on the upper ends 115 of the posts 116. The construction is such, obviously, that by turning the nuts 117, the entire roof structure may be adjusted up or down, in the building of the filling station.

50 Inclined turnbuckle braces 118 connect the posts 116 with the superstructure that carries the roof 119, the roof being mounted on beams 120, located above the channels 104, the bars 106, and 10 elsewhere, if desired.

55 The water supply pipe 121 of Fig. 10 is located in the superstructure, and to it are connected the flexible hose members 122, raised to an inoperative position by the weight, pulley and cord 15 mechanism hereinbefore described, and designated, in the modification, as a whole, by the numeral 123.

60 Hollow beams 124 are disposed in the superstructure, above the ceiling 110, and extend between the Z-bars 106. Each of the hollow beams 124 is provided at its end with a gauge glass 125, located in the superstructure. From the hollow beams 124, pipes 126 extend downwardly through the standards 87, to faucets corresponding to those shown in Fig. 1, the said faucets being disposed, as before, in cabinets 127 on the casings 89 of the standards 87, the cabinets having the movable closures 128, hereinbefore mentioned. Access is had to the roof 119 by foldable ladder 30 rungs 129, located on one of the standards 87, and on the roof frame 101, as shown in Fig. 8.

65 The filling connections for the hollow beams 124 extend above the roof 119 and are marked by the numeral 130. The filling operation may be brought about by taking off the caps 131 on the filling connections. The filling connections 130 are joined at 132 to a manifold pipe 133 that carries air under pressure, the intermediate portion of the manifold pipe 133 being connected 40 to a fluid pressure supply pipe 134.

70 The general operation of the form shown in Figs. 8, 9 and 10 will be understood readily in view of what has been stated in connection with the form first described. Air pressure is put on the hollow beams 124 by way of the pipe 134, and the liquid leaves the beam and passes to the faucets through the pipes 126.

75 Figure 11 shows a slight modification which may be employed where it is desired to have a greater variety of oils and is provided for hereinbefore. According to Fig. 11, any desired number of containers 500, resembling the containers 124 of Fig. 10, for instance, may be placed under ground, or elsewhere, each container having a filling pipe 501 and an air pressure line 502. The delivery pipe for each container 500 is marked by the numeral 503, leading upwardly to a faucet 504, which may be placed among the lower faucets 51 or 58 of Fig. 4.

80 Having thus described the invention, what is claimed is:

1. Dispensing mechanism for a filling station of the type in which a motor car is driven between spaced standards and beneath a canopy supported at its sides and intermediate its ends on the standards, the dispensing mechanism embodying vertical standards carrying the canopy and spaced to receive a motor car between them, the lower portions of the standards being hollow, means for supporting the standards at their lower ends on the ground, said means embodying hollow, horizontal members connected intermediate their ends to the hollow lower portions of the standards, the hollow horizontal members and the

lower portions of the standards constituting liquid-containers, and inlet and outlet means for the said liquid-containers.

2. Dispensing mechanism for a filling station of the type in which a motor car is driven between spaced standards and beneath a canopy supported at its sides and intermediate its ends upon the standards, the dispensing mechanism embodying spaced pairs of vertical standards having hollow upper portions, approximately horizontal hollow beams located at each side of the station, the beams at each side of the station extending from the standards toward opposite ends of the station, the beams carrying the canopy, the inner end of each beam being connected to one of the standards and being in communication with the hollow upper portion of that standard, whereby the beams and the hollow upper portions of the standards form liquid-containers, means for admitting liquid to said liquid-containers, means on the hollow upper portions of the standards for drawing liquid from said liquid-containers, and means for supporting the standards from the ground.

25 3. Dispensing mechanism for a filling station of the type in which a motor car is driven between spaced standards, the dispensing mechanism embodying vertical standards, spaced to receive a motor car between them, and having hollow upper portions, a hollow member connecting the hollow upper portion of the standard at one side of the station with the hollow upper portion of the standard at the opposite side of the station and communicating therewith, the hollow member and the hollow upper portions of the standards forming a liquid-container, means for admitting liquid to said container, means on the hollow upper portions of the standards for drawing liquid from said container, and means for supporting the standards from the ground.

40 4. A device of the class described, constructed as set forth in claim 3, in combination with horizontally disposed, approximately parallel cylindrical tanks mounted upon the hollow member and supported thereby, the tanks being arranged transversely of the hollow member, means for admitting liquid to the tanks, and means for holding the tanks against rolling movement on the hollow member, in fixed spaced relation to each other and to the standards, the last-specified means embodying rigid outlet pipes connected to the lower portions of the tanks and to the standards, and extended downwardly along the standards, the last-specified means also comprising a fluid pressure pipe disposed above the standards, and above the tanks, and having branches extended downwardly and connected to the upper portions of the tanks and to the upper portions of the standards, some of the branches communicating with the upper portions of the tanks, and others of the branches communicating with the hollow upper portions of the standards.

45 5. Dispensing mechanism for a filling station of the type in which a motor car is driven between spaced standards and beneath a canopy supported at its sides and intermediate its ends on the standards, the dispensing mechanism comprising vertical standards spaced to receive a motor car between them, each standard comprising vertical pipes, approximately parallel hollow intermediate and terminal members built into the canopy and forming a supporting part thereof, the hollow members also constituting liquid-

5 5 containers, outlet pipes connected to the liquid-containers and leading downwardly along the standards, means on the lower portions of the outlet pipes, adjacent to the standards, for governing the flow through the outlet pipes, means for holding the hollow members together, hollow beams disposed on opposite sides of the pipes of the standards and projecting outwardly in opposite directions, with respect to the pipes of the standards, the hollow beams being arranged at right angles to the hollow members and being connected at their outer ends to the terminal hollow members in supporting relation thereto, the hollow beams being connected at their inner ends to the pipes of the standards, in communicating relation therewith, the terminal hollow members constituting the closures for the outer ends of the hollow beams, whereby hollow beams and the pipes of the standards will constitute liquid-containers, means on the pipes of the standards for drawing liquid from the last-specified containers, and means for supporting the pipes of the standards from the ground.

6. Dispensing mechanism for a filling station of the type in which a motor car is driven between spaced standards and beneath a canopy supported at its sides and intermediate its ends upon the standards, the dispensing mechanism embodying standards spaced to receive a motor car between them, each standard comprising a pair of inner vertical pipes, and a pair of outer vertical pipes, horizontal outer beams built into the canopy at the sides of the station and having their inner ends secured to and in communication with the outer vertical pipes of the standards, the beams and the pipes constituting liquid-containers, the weight and the liquid load of which are carried by the outer vertical pipes, means for admitting liquid to the said containers, means on the outer pipes for drawing liquid from the said containers, other hollow beams connecting the inner pipes of one standard with the inner pipes of the opposite standard, said other beams and the inner pipes of the standards constituting liquid-containers the weight and the liquid load of which are carried by the inner vertical pipes, means for admitting liquid to the last-specified containers, means on the inner pipes, for drawing liquid from the last-specified containers, and means on the lower portions of the pipes of the standards for supporting the standards from the ground.

7. Dispensing mechanism embodying vertical standards, means for supporting the standards at their lower ends on the ground, hollow beams extended between the standards and arranged approximately in a horizontal plane, the beams forming liquid containers, means for supporting the hollow beams upon the standards at such a height above the ground that a motor car may be driven beneath them, the beams being long enough to space the standards apart sufficiently so that a motor car can be driven between the standards, a roof into which the beams are built, the beams having filling connections extended upwardly through the roof, the roof serving as a walking-place for an operator wishing access to the filling connections, liquid discharge means leading downwardly from the beams, along the standards, and means for opening and closing the liquid discharge means from a point on the ground.
